ABEL NUTTING, OF QUINCY, MASSACHUSETTS.

Letters Patent No. 71,902, dated December 10, 1867.

IMPROVED SNOW-PLough.

The Schedule referred to in these Letters Patent and making part of the same.

TO ALL WHOM IT MAY CONCERN:

Be it known that I, ABEL NUTTING, of Quincy, in the county of Norfolk, in the State of Massachusetts, have invented a new and improved Snow-Plough for Railway-Tracks; and I do hereby declare that the following, taken in connection with the drawings which accompany and form part of this specification, is a description of my invention sufficient to enable those skilled in the art to practise it.

Prior to my invention, snow-ploughs, for the purpose of clearing railway-tracks, have all had one general method of operation, though varying considerably in form or shape, said method being the removal of the snow to one or both sides of the track, by the action thereupon of inclined bodies, propelled against the snow by locomotives. Such ploughs operate well except where they meet with snow in bodies sufficient to overcome the momentum with which the ploughs are propelled, in which cases they become wholly inoperative, and then the track has to be cleared by hard labor.

My invention consists in mounting upon a shaft, in front of the locomotive or train, a set of blades, the edges of which in their revolution describe the cutline of a conical body, the axis of rotation being substantially parallel with the track, so that the blades, when propelled forward and rotated at the same time, act upon the snow to cut into it and throw it to one side or the other of the track, according to the direction of the rotation given to the apparatus.

The drawing shows in plan an apparatus embodying my invention.

The frame *a* represents the frame of a locomotive, or of a truck, which may be pushed ahead of the locomotive on the track, the rotating-shaft *b* being supported in suitable bearings on the frame. On the shaft are fixed heads, *c c'*, these serving to hold the blades *d*, which I prefer to have made and set on angles with the shaft, as shown, so that in their rotation they will cut into the snow gradually along their length, and thus lessen the strain upon the apparatus; and to facilitate still further the easy working of the device, I prefer to extend the blades to the end of the shaft, which has a pointed termination, as shown.

The peculiar construction and arrangement of the blades shown and described is not of the essence of my invention, and may be varied as experience may show to be desirable; as, for example, the heads may be dispensed with, and the blades may be united directly to the shaft, and braced to each other, so as to obtain the requisite strength for service.

The wheels of the truck are marked *e*, and there is shown on their axle a bevel-gear, from which, by any suitable system of gearing, rotary motion is given to the shaft *b*, so that in many cases the rotation of the shaft *b* and its blade *d* is effected by the propulsion of the train along the track. But as in some cases it is impossible, by the momentum of a train, to propel it with a plough in advance through drifts, I propose to connect, by means of suitable gearing, the shaft *b* with an engine arranged on the frame *a*, which engine, when it is employed to rotate the plough, is not employed to propel the train, the engine being supplied with steam from the boiler of the locomotive which propels the train, or from a separate boiler carried on the frame *a*. And it may here be observed that the gearing which rotates the plough may be arranged so that, by change of the gears as to position, it will rotate the plough to the right or to the left, as circumstances may require, whether the rotation is effected from the propulsion of the train or from a separate and special engine.

To widen the clearance made by the plough, inclined wings or shears *f* may be secured to the frame, and to clear away the snow left under the plough in the form of a concave, additional inclines or shares are to be employed, reaching from a point under the centre of the shaft *b*, and extending downward near the rails, and outward, substantially as shown in red lines on the drawing.

To operate well in practice, the length of the shaft inboard on the locomotive, or on the supplemental truck, should exceed in length the overhanging or outboard length of the shaft around which the blades are arranged.

I claim, for the purpose described—

The rotary plough, arranged to operate substantially as set forth.

Also, in combination with such a plough, inclines or shares, fixed, with respect to the frame by which they are supported, substantially as described.

ABEL NUTTING.
